UNITED STATES PATENT OFFICE

166,588

COMBINED WINDSHIELD CLEANER AND
COIN RECEPTACLE

David Brody, Clinton, and Sidney Coleman, Maynard, Mass., assignors to Van Brode Milling Co., Inc., Clinton, Mass., a corporation of Massachusetts

Application May 5, 1951, Serial No. 15,082

Term of patent 7 years

(Cl. D9—6)

To all whom it may concern:

Be it known that we, David Brody and Sidney Coleman, citizens of the United States and residents, respectively, of Clinton, Commonwealth of Massachusetts, and of Maynard, Commonwealth of Massachusetts, have invented a new, original, and ornamental Design for a Combined Windshield Cleaner and Coin Receptacle, of which the following is a specification, reference being had to the accompanying drawing, forming part hereof.

Fig. 1 is a front elevation of a combined windshield cleaner and coin receptacle, showing our new design;

Fig. 2 is a rear elevation of the same;

Fig. 3 is a section taken on line 3—3 of Fig. 1; and

Fig. 4 is a section taken on line 4—4 of Fig. 1.
We claim:

The ornamental design for a combined windshield cleaner and coin receptacle, as shown.

DAVID BRODY.
SIDNEY COLEMAN.
